UNITED STATES PATENT OFFICE.

ISAAC CORNTHWAITE GREEN, OF GLASGOW, SCOTLAND, ASSIGNOR OF ONE-HALF TO
FREDERICK ERNEST REBECK, OF QUEEN'S ISLAND, BELFAST, GREAT BRITAIN.

INTERNAL-COMBUSTION SINGLE-ACTING ENGINE CYLINDER.

Application filed December 14, 1923. Serial No. 680,764.

To all whom it may concern:

Be it known that I, ISAAC CORNTHWAITE GREEN, a British subject, residing at 15 York Avenue, Jordan Hill, Glasgow, Scotland, have invented certain new and useful Improvements in Internal-Combustion Single-Acting Engine Cylinders, of which the following is a specification.

This invention relates to internal combustion single-acting engine cylinders of the type which includes a separate casting for the cylinder liner, and has for its object to provide a special construction of liner, which enables the useful life of the latter to be prolonged.

It is found that the part of the cylinder liner surface which is nearest to the combustion chamber is most subject to wear due to the abrasive action of the piston and piston rings. The other end of the cylinder liner, viz, the end remote from the combustion chamber, is subject to comparatively little wear.

The present invention consists essentially in constructing the cylinder liner so that it is reversible or symmetrical end for end, whereby when one end is worn the liner may be reversed end for end and used for a further period. In this way the useful life of the liner is approximately doubled.

The accompanying drawing illustrates one construction of my improved cylinder, the drawing showing the cylinder in section.

With reference to the drawing, the cylinder cover or breech A is secured by means of bolts or screws B to the liner C, which is symmetrical end for end, so that the flange E, which abuts the cylinder cover A, is an exact duplicate of the flange F at the opposite end of the liner. The jacket D may be in one piece or of two or more pieces connected by bolts G, or any other well known means.

When the liner C has become badly worn by the abrasive action of the piston and rings at the end of the liner nearest flange E, then the liner is removed and replaced so that the position previously occupied by flange E is now occupied by flange F and vice-versa. The worn portion of the liner is then remote from the combustion chamber, whereas the comparatively unworn part of the liner is adjacent to the combustion chamber. In this way the useful life of the liner is practically doubled.

It will be understood that the particular construction illustrated in the drawing is by way of example only and that the invention covers any arrangement of a cylinder liner which is symmetrical end for end and which may have a flange or be capable of being flanged at each end, whereby either end may be fixed to the cylinder cover or breech.

The particular form of liner illustrated is one of many forms which might be adopted in accordance with the invention. In the same way, alternative forms of cylinder jacket might be used in connection with the invention.

I claim:

1. An improvement in motor cylinders for single acting combustion engines of that kind in which one end of the cylinder liner is connected with the cylinder cover so as to allow the liner to freely expand downwards, comprising, a cylinder cover, and a cylinder liner, each end of the liner being provided with means for fastening the liner to the cover.

2. An improvement according to claim 1, the ends of said cylinder liner being symmetrical.

3. An improvement according to claim 1, said means for fastening the liner to the cover, being fastening flanges.

4. An improvement according to claim 1, the ends of said cylinder liner being symmetrical, said means for fastening the liner to the cover, being fastening flanges.

5. An improved cylinder liner, each end of the liner having fastening means for alternatively connecting the liner to a cylinder cover, whereby the liner can be reversed end for end relative to the cover, in order to prolong its life.

6. An improved cylinder liner according to claim 5, said fastening means being symmetrical.

7. An improved cylinder liner according to claim 5, said fastening means being connecting flanges.

In testimony whereof I affix my signature,

ISAAC CORNTHWAITE GREEN.

Witnesses:

A. G. MARSHALL,
ALBERT E. BURNS.
